I. L. STERN.

CIGAR POUCH.

APPLICATION FILED MAR. 1, 1915.

1,385,454.

Patented Mar. 30, 1920.

UNITED STATES PATENT OFFICE.

IRVING L. STERN, OF NEW ORLEANS, LOUISIANA, ASSIGNOR TO HAVANA-AMERICAN CO., OF NEW YORK, N. Y., A CORPORATION OF NEW JERSEY.

CIGAR-POUCH.

1,335,454.

Specification of Letters Patent. Patented Mar. 30, 1920.

Application filed March 1, 1915. Serial No. 11,222.

To all whom it may concern:

Be it known that I, IRVING L. STERN, a citizen of the United States, residing at New Orleans, in the parish of Orleans and 5 State of Louisiana, have invented new and useful Improvements in Cigar-Pouches, of which the following is a specification.

This invention relates to pouches, and particularly to pouches intended to be used 10 for carrying tobacco or cigars in one's pocket. Cedar wood is believed by tobacconists to have desirable qualities when used in containers or boxes for tobacco, and this 15 reputation of cedar wood in this connection is so widely known to tobacconists and tobacco users that the association of this wood with packages of tobacco appears to enhance the selling qualities of the tobacco sold. In packages such as cigar boxes cedar 20 wood may be readily employed.

One of the objects of the present invention is to produce a very light and serviceable pouch which can be carried in one's pocket and which evidently embodies cedar wood 25 in its construction giving the wall of the pouch the desirable qualities of cedar wood, and also enhancing the selling qualities of the tobacco or cigars which the pouch contains.

30 Further objects of the invention will appear more fully hereinafter.

The invention consists in the combination of parts and in the features to be described in the following specification, all of which 35 contribute to produce an efficient and serviceable pouch. The preferred embodiment of the invention is illustrated in the accompanying drawing, in which—

Figure 1 is a perspective of a pouch embodying my invention, a portion of the same being broken away to illustrate a detail of its construction.

Fig. 2 is a side elevation partly broken away, showing the preferred form of the 45 composite sheet out of which I form the wall or walls of the pouch.

Fig. 3 is an end elevation of the composite sheet shown in Fig. 2.

Fig. 4 is a perspective showing the preferred embodiment of the bottom or end wall of the pouch.

Fig. 5 is a perspective showing the com-

posite sheet in the act of being applied to the bottom or end wall.

Fig. 6 is a vertical cross-section through 55 the finished pouch partly broken away.

Fig. 7 is a perspective showing a short portion of a binding tape which I prefer to use at the corners of the pouch.

Fig. 8 is a plan in partial section of the 60 pouch, the middle portion of the same being broken away.

Fig. 9 is a perspective showing one of the 65 walls of the pouch and illustrating details of its construction.

The pouch is preferably formed of a composite sheet 15, preferably including a thin film sheet or membrane of cedar wood. This sheet or film has substantially the same thickness as thin writing paper. It is so 70 frail and thin that when held up to the light it displays numerous translucent points indicating the presence of the interstices or pores so characteristic of cedar wood. Before forming the composite sheet 75

I prefer to form the cedar sheet 16 with score lines such as the lines 17, which are parallel with each other, and which indicate points at which the composite sheet is to be folded to form the pouch, and these 80 lines 17 of course correspond or coincide with the outer edges of the corners of the finished pouch. To the facing sheet 16 of cedar film I attach a backing sheet 18, which is preferably of the same shape and area 85 as the facing sheet. I attach these sheets together throughout their entire area by means of an adhesive thick flour paste. This paste is then permitted to dry for from twenty-four to thirty-six hours. For the 90

purpose of giving the finished pouch a more finished appearance and also to increase its durability I prefer to include in the composite sheet a lining sheet 19, which is formed of thin paper and preferably printed 95 on its exposed face so as to resemble the grain of cedar wood. This lining sheet 19 has three dimensions which are the same as those of the other sheets, but this sheet 19 is slightly deeper so that when superposed upon the other sheets a projecting margin 20 is formed at the upper edge. This sheet 19 is attached throughout its entire area to the inner face of the backing

sheet 18 preferably by means of thick flour paste, and this paste is then permitted to dry for from twenty-four to thirty-six hours. The projecting strip 20 is folded 5 down over the upper edge 21 of the sheets 16 and 18 so as to form a trimming 22 which will appear at the mouth 23 of the complete pouch (see Fig. 1). The sheet 18 reinforces the cedar film and prevents its breaking at 10 the corners. Part of this strengthening effect is due however to the permeability of the cedar film or membrane, the pores of which absorb the paste. It is advisable to use thick paste for this purpose and to allow 15 the amount of time stated for the paste to be absorbed by the cedar film. A pouch formed simply of such a composite sheet would readily collapse and if pressed flat would tend to break where folded.

20 In order to form a reinforcing wall and bottom for the pouch and give it a relatively thin and flat form, opposite the mouth 23 I prefer to provide a small elongated block 24 such as that illustrated in Fig. 4, and this 25 block is preferably formed of cedar wood and is of rectangular form. The length of this block determines the greatest width of the pouch. In order to form the pouch from the composite sheet and the bottom or 30 end wall 24, I prefer to fold the composite sheet on the lines 17, which correspond to the corners of the finished pouch, and apply the lower edge of the composite wall continuously to the side edges of the block 24, 35 preferably in the manner illustrated in Fig. 5. In doing this flaps 25 are formed which may overlap each other, as indicated in Fig. 8, to form one of the narrow vertical walls of the pouch. On the inner side of 40 this vertical wall I prefer to provide a vertical liner strip 26 which may be made of a strip of the same material as the lining or sheet 19. This strip is attached by an adhesive to the inner face of the inner flap 25 45 and also to the inner side of one of the side walls 27 of the pouch, preferably as indicated at Fig. 8. At the middle point of the ends of the block 24, and also on the sides, I prefer to provide fastening devices 50 such as the brads 28, which are driven through the sheet into the block. In order to give the pouch a neat and trim appearance I prefer to provide edging strips 29 which are preferably made of the printed 55 cedar paper out of which the lining sheet 19 is formed. These edging strips extend from the trimming strip 22 at the mouth of the pouch down to the bottom edge where they

are folded so as to form neat corner folds at the point where the strip extends along 60 the bottom of the pouch.

Although I prefer to employ paper to form the backing sheet 18 I may, if desired, employ other material, such as cloth, which may be muslin if desired.

65

The cedar film is natural cedar wood cut into very thin flexible sheets, and is a readily procurable commercial product.

The rigid end wall or bottom 24 has squared ends as shown which operate to reinforce the frail shell or body of the pouch and prevent the side walls of the pouch from being crushed together so as to bend the composite sheet double. The composite sheet can be bent substantially at right angles as on a corner but can not be bent double without breaking. This the rigid wall 24 with its squared ends 24^a prevents.

It is understood that the embodiment of the invention set forth herein is only one of the many embodiments or forms the invention may take, and I do not wish to be limited in the practice of the invention nor in my claim to the particular embodiment set forth.

85

What I claim is:

A pocket pouch for tobacco products and having a rectangular cross-sectional contour and adapted to be carried in the pocket of the user, said pouch comprising a rectangular wall composed of a thin cedar sheet, an intermediate reinforcing backing sheet and a paper lining sheet pasted together face to face, said lining sheet being of relatively greater height than both the cedar sheet and the backing sheet to produce a marginal portion adapted to be folded over the upper edges of the cedar sheet and the backing sheet to constitute a binder and trimming for the mouth of the pouch, one of the vertical end sections of the wall being formed by overlapping and securing the adjacent free vertical edge portions of the walls, a block of rigid material inserted within the lower end portion of the rectangular wall 105 and fastened thereto to form a bottom therefor, and exterior edging strips applied to the edges and corners of the pouch at the sides and bottom thereof.

95

In testimony whereof I have hereunto set 110 my hand in presence of two subscribing witnesses.

IRVING L. STERN.
